TRANSMIT RECEIVE SWITCHING SYSTEM
FOR PULSE COMMUNICATION SYSTEMS

Louis D. Smullin, Arlington, and Jerome B. Wiesner, Boston, Mass., assignors, by mesne assignments, to the United States of America as represented by the Secretary of War

Application April 18, 1944, Serial No. 531,654

6 Claims. (Cl. 178—44)

1

This invention relates to a communication system and more particularly to a system of this character wherein radio transmitters and receivers operate in close proximity to each other. In many systems, such as radar systems, it is customary to pulse a transmitter at fixed intervals and utilize received echoes for determination of target data. Such systems may have separate or common antennae.

In a system of the above character, the amount of power radiated from the antenna during transmitter operation is extremely large in comparison to the amount of power necessary for receiver operation. Irrespective of whether the transmitter and receiver have a common antenna or separate antennae, the problem of protecting the receiver from excessive energy input during transmitter operation is present. In particular where the transmitter and receiver have an antenna in common and may in fact be connected in the same communication channel to such an antenna, it is necessary to provide suitable switching means for protecting the receiver during transmitter operation.

One manner in which a receiver may be protected involves the use of an overload switch comprising a gaseous discharge gap which is adapted to be broken down and thus alter the transmission characteristics of the communication channel between receiver and antenna. Such a system is particularly useful where the communication channel is in the form of a wave guide. A switch of this character is disclosed in the co-pending application of Harold K. Farr, Serial Number 488,098, filed May 22, 1943. Thus by changing the effective resistance across a portion of guide, it is possible to accomplish a switching action which may cut off the receiver during transmitter operation and cut in the receiver at other times.

A switching action as described above in general relies upon a potential difference due to the wave front generating or increasing the number of ions in the gap so that a gaseous discharge is effected. Even with the extremely steep wave fronts employed, it has been found that the mechanism of ionization for breaking down the gap requires a period of time which is appreciable in comparison to the variation of voltage with time. Thus it frequently occurs that before the switch or gap has time to act, a damaging amount of energy has passed on to the receiver. This amount of energy may temporarily or permanently damage certain parts, particularly crystal mixers or detectors.

The invention hereinafter described provides a means for protecting the receiver and allied equipment and preventing a dangerous wave front from being passed to the receiver during the time which is required for the switch to change its condition.

The invention in general comprises the insertion into the line between receiver and switch of a reactance element having low resistance. Such a reactance element may take the form of a cavity resonator having a satisfactory Q. It is well known in this art that the Q of any device or circuit may be defined as the ratio of energy stored to energy dissipated. The effect of a high Q reactance is to utilize the initial burst of energy for generating oscillations therein and thereafter such energy is given out with little loss but at a reduced level and over a longer period of time.

The efficiency or Q of the reactance will determine what might be termed a distorting action of the voltage front on the receiver. In general, the Q should be high enough so that the protection afforded the receiver will endure for just the period of time required for switch operation. However, care must be exercised to prevent too high a reactance from being inserted. Thus in the use of radar systems, the sharp pulses used represent video bands of frequency which must be preserved. The use of reactances having excessively large Q's will tend to reduce the video range and thus impair the sharpness of pulses to be received.

In the drawing, Fig. 1 is a time-power curve showing the energy passed by the usual switching device. Fig. 2 is a block diagram of a basic communication system embodying the present invention, and Fig. 3 is the time-power curve at the receiver obtained through use of the invention.

Referring to Fig. 1, it will be seen that a sharp energy peak 5 passes through the usual switching device at the beginning of a transmitted pulse. The curve levels off as shown at 6 when the changed electrical conditions cause switch operation. This initial peak 5, however, generally is of sufficient magnitude to cause damage to the receiver crystal, and greatly limit its useful life.

Referring to the block diagram of Fig. 2, it will be seen that a reactance element, shown in the diagram as a "High Q-cavity," is connected between the switch and the crystal of the receiver. It is well known that the time necessary to build up energy in a cavity is equal to the time required for the stored energy to die out

and is a function of the decrement of the cavity or an inverse function of the Q.

The cavity or other reactance element may have, in actual practice, a Q of the order of 200 or 300 and may go higher, if the video range is not too great.

With a reactance of this character, as disclosed, the energy stored therein will be given out at the time the switch operates so that in effect the energy peak will be broadened out and reduced. The distance between the cavity and switch on the one hand and between cavity and receiver on the other hand in terms of wave length is not important. If tuning with the cavity is to be utilized, then the disposition of a reactance cavity must be carefully determined.

What is claimed is:

1. In a system having a guide for electromagnetic waves into which are introduced at different times relatively high power and low power pulses of electromagnetic energy, receiving means for said low power pulses connected to said guide by electromagnetic wave conducting means including switch means interposed between said receiving means and guide, said switch means being responsive to any one high power pulse and effective after an interval following initiation of said one pulse which is short compared to the length of said one pulse, to reduce greatly the transmission of energy therethrough, and a frequency selective filter means connected between said switch means and receiving means to permit only a portion of the energy passing through said switch means during said interval to pass through said filter means.

2. In a system having a guide for electromagnetic waves into which are introduced at different times relatively high power and low power pulses of electromagnetic energy, receiving means for said low power pulses connected to said guide by electromagnetic wave conducting means including switch means interposed between said receiving means and guide, said switch means being responsive to any one high power pulse and effective after an interval following initiation of said one pulse which is short compared to the length of said one pulse, to reduce greatly the transmission of energy therethrough, and a cavity resonator which acts as a frequency selective filter interposed between said switch means and receiving means to permit only a portion of the energy passing through said switch means during said interval to pass through said resonator.

3. In a system having a guide for electromagnetic waves into which are introduced at different times relatively high power and low power pulses of electromagnetic energy, receiving means for said low power pulses connected to said guide by electromagnetic wave conducting means including a first cavity resonator interposed between said receiving means and guide and having therein a pair of electrodes forming a discharge gap across which a discharge is established by any one high power pulse after an interval following initiation of said one pulse which is short compared to the length of said one pulse, said discharge being effective to reduce greatly the transmission of energy through said resonator, and a second cavity resonator which acts as a frequency selective filter interposed between

said first resonator and receiving means to permit only a portion of the energy passing through said first resonator during said interval to pass through said second resonator.

4. Apparatus for use in a system having receiving means for low power pulses conductively connected to transmission means into which are fed at different times high power and low power pulses of electromagnetic energy, comprising switch means adapted to be interposed in the connection between said transmission means and receiving means, said switch means being of the type responsive to any one high power pulse to reduce substantially the transmission of energy therethrough after an interval following initiation of said one pulse which is short compared to the length of said one pulse, and a resonant circuit coupled to said switch means to be interposed between said switch means and receiving means in said connection, said resonant circuit having a frequency band width greater than the band width of the low power pulse but less than the band width of that portion of the high power pulse energy that is passed by said switch means.

5. Apparatus for use in a system having receiving means for low power pulses conductively connected to transmission means into which are fed at different times high power and low power pulses of electromagnetic energy, comprising circuit means interposed in the connection between said transmission means and receiving means responsive to any one high power pulse to reduce substantially the transmission of energy therethrough after an interval following initiation of said one pulse which is short compared to the length of said one pulse, and a resonant circuit coupled to said circuit means and interposed between said circuit means and receiving means in said connection, said resonant circuit having a frequency band width greater than the band width of the low power pulse but less than the band width of that portion of the high power pulse energy that is passed by said circuit means.

6. In a system having a guide for electromagnetic waves into which are introduced at different times relatively high power and low power pulses of electromagnetic energy, receiving means for said low power pulses, electromagnetic wave circuit means connected between said receiving means and guide, said circuit means being responsive to any one high power pulse and effective after an interval following initiation of said one pulse which is short compared to the length of said one pulse, to reduce greatly the transmission of energy therethrough, and a frequency selective filter means connected between said circuit means and receiving means to permit only a portion of the energy passing through said circuit means during said interval to pass through said filter means.
